DOLL, PARTS OF DOLLS, AND METHOD OF
MANUFACTURING THE SAMEAndrew Hajdu, Brooklyn, N. Y., assignor to The
Kelly-Springfield Tire Company, Cumberland,
Md., a corporation of New Jersey

Application November 28, 1932, Serial No. 644,649

10 Claims. (Cl. 46—40)

This invention relates to a new and improved doll and certain parts thereof and to a method of manufacture and, with regard to its more specific features, relates to a doll having separately formed and movable members. All such dolls are included in the term, whether they mimic human beings, animals or are entirely fanciful.

One of the objects of my invention is to provide a durable doll which has a torso of resilient compressible material attractive to children and free from any metallic or other rigid elements throughout substantially the entire torso. Another object is to provide such a doll in which the head and limbs may be attached by local means which provide the required degree of free movement and avoid the necessity of any connection between such elements except such as is provided by the covering of the torso. A further object is to devise a method of manufacturing such a doll quickly, easily and cheaply.

Other objects of my invention will be in part obvious and in part set forth in the following description and drawing in which:

Fig. 1 is a partial cross section of a doll embodying my invention in its preferred form;

Fig. 2 is a perspective view of the torso member of said doll;

Fig. 3 is a side elevation of the torso cover;

Fig. 4 is a plan view of the neck member viewed from its under side.

Referring now to the drawing, 1 is a torso or body member formed of a resilient compressible material, such as sponge rubber and having the normal shape of its exterior such as is desired for the torso of the doll. This torso may, if desired, have a central cavity 2 for the purpose of reducing the amount and weight of the material required and to increase its resiliency. The torso 1 is provided also with a recess 3 at its upper end adapted to seat a neck member 4, and is preferably provided also with a recess 5 at each point where a limb is to be attached. Surrounding each recess 5 it is preferable to provide a level bearing surface 5a. When the torso is provided with a cavity 2 it is possible to associate therewith air operated sound mechanism of any usual type, conventionally indicated at 21, by attaching said mechanism either to the neck member 4 or to some part of the head 13; the compression of the torso forces the air through the mechanism to cause sound to emerge through the neck opening.

6 is a cutaneous torso cover formed of readily

collapsible material, such as latex or sheet rubber, of a thickness preferably about one-sixtieth of an inch, and with an opening 7 at its neck end. By the term "readily collapsible" is meant a condition in which the torso cover is so pliable as to permit any portion of its interior to be protruded through the opening 7 without injury to the cover or substantial effort. The ready collapsibility of the torso cover permits the use of a hammer or other tool upon the inside of the torso cover at the desired point for the attachment of limbs by the method hereinafter described. The torso cover is flexible in the regions surrounding the opening 7 and preferably throughout substantially its entire area in order to permit the neck opening to be expanded for the reception of the torso and neck member as hereinafter described and to conform to said parts. It has substantially the shape of the combined torso 1 and neck member 4 which it is to enclose, but is slightly smaller so as to provide a snug fit.

The torso cover 6 is preferably provided at the area where it is to be attached to the limbs with patches 8 of fabric or other material which is not readily torn and which has a surface which gives less friction upon the attached limb than rubber would have. These patches are attached to the exterior of the torso cover 6 in any convenient manner such as by the use of rubber cement. They may be of any desired size provided that they do not extend so far as to limit the necessary elasticity of the torso cover, particularly in the region surrounding the opening 7.

The limbs 9 may be of any desired material but are preferably formed of rubber or other durable substance which is resilient and capable of compression without injury. In my preferred embodiment they are formed of hollow molded rubber of a thickness sufficient to maintain the limb in normal shape when not under compression. The end of each limb which is intended for attachment to the body is provided with an internal annular groove 9a just within the end. Into this groove is seated a mating annular projection 10a on the attachment member 10 which is a relatively rigid disk, preferably of wood, and provided with a centrally located pin 11 having a head at one end and a bendable pointed shaft protruding from said disk. The diameter of the flange 10a is greater than the opening at the end of the limb 9 in order to assure a snug fit when the parts are in assembly. The pin 11 pierces the torso cover and its reinforcing patch at the desired point of

attachment and is then preferably passed through additional reinforcement in the form of a washer 12 before being anchored as by being bent against this washer. Such bending may, if desired, take the form of a spiral spring as shown in Fig. 1 thus providing a resilient anchorage. The washer 12 is relatively rigid, with a smooth inner surface and a diameter larger than that of the adjacent recess 5 of the torso 1 and preferably as great as that of the attached end of the adjacent limb. The bent portion of the pin 11 may rotate freely against the surface of the washer 12 and within the recess 5 or, if desired, may contact somewhat with the walls of said recess in order to provide the desired degree of friction to resist accidental but to permit intended movement of the limb.

The doll's head 13 may be of any convenient construction such as, for example, of composition material, having a hollow center 14 and a socket 15 where it is to adjoin the neck and being provided with a fixed member 16 within the hollow center to which the head attaching means can be connected. The hollow center 14 may be connected with a passage through the mouth of the doll and also to the passage 18 and sound mechanism 21, serving to permit escape of air and sound when the torso is compressed. The head 13 is connected with the neck member 4 which is relatively rigid as compared with the torso cover 6, and serves to support it in the neck region in order to provide a firm foundation upon which the head may rest and turn. In the preferred embodiment shown, the neck member 4 is a wooden plug having a projecting member 17 conforming in shape to the recess 3 of the torso 1 to which it is preferably affixed as by rubber cement. Centrally of the neck member 4 is a passage 18 through which runs a spring or other elastic member 19, the lower end of which is held within the neck member 4 by a pin 20 crossing below or driven through the projection 17 and the upper end of which is held within the head as by being hooked over the fixed member 16.

The completed doll may thus be entirely of rubber so far as the exposed parts of the body and limbs, and may give the effect of having the body and limbs entirely of rubber for the reason that the torso and limbs may be compressed to any desired extent without encountering any hard objects and without permanent distortion or injury to the doll. The only exceptions to this general resiliency are the small areas adjoining the junction of the limbs and head with the body. The doll has the further desirable quality of being durable, since it is free from skeleton-like members and elastic connections between limbs which are likely to be broken or wear out before the exterior of the doll.

In constructing the doll, the torso 1, the torso cover 6, the limbs 9 and the head 13 are all separately constructed. The limbs are then attached to the torso cover 6 and for this purpose the torso cover may be collapsed until any desired point, as for example one of the reinforced patches, is brought into registration with the opening 7 or even protruded therefrom. The pin 11 of an attachment member 10 is then thrust through the torso cover or its reinforcement from the outside of the cover, the pin then passed through a washer 12 and anchored as by bending on the inside by the use of a hammer or other means as shown in Fig. 1.

75 The neck member 4 is then connected with the

spring 19 by the pin 20 and its projection 17 inserted in the recess 3 of the torso where it may be cemented or otherwise fastened into place. The opening 7 in the torso cover 6 is then expanded and the torso 1 may be compressed also so that the torso with the neck member 4 is inserted within the torso cover 6; after which the torso cover is allowed to contract upon the torso and neck member. The upper end of the spring 19 is then stretched and connected within the opening 15 of the head 13 and hooked over the member 16 so that the head rests upon the torso cover above the neck member 4, when the tension on the spring is relaxed.

The limbs 9 are then attached by expanding the opening in the body end of each to pass over the disk 10 until the annular projection 10a seats within the groove 9a, the attachment being made permanent if desired by gluing or cementing the limbs 9 to the members 10 at their adjacent surfaces.

It is to be understood that the order of certain steps may be changed without departing from the scope of this invention. For example, the member 18 may be attached to the limb 9, if desired, before the pin 11 is passed through the torso cover 6, the neck member 4 may be attached to the head 13 before the neck member is inserted within the torso cover 6 or seated in the recess 3. Likewise any other form of connection may be used between limbs and torso cover and between head and torso, provided that it does not interfere with the insertion of the torso 1 in the torso cover 6. The neck member 4 may, if preferred, be cemented to the under side of the torso cover instead of to the torso, or may even be left uncemented, holding its place merely by the elastic tension of the torso cover. It is also to be understood that the exterior portions of the doll may be provided with natural color and other features as is known to the art.

Since certain changes may be made in carrying out the above method and in making said doll and parts without departing from the scope of the invention, it is intended that all matter contained in the above description shall be interpreted as illustrative and not in a limiting sense.

Having described my invention, what I claim as new and desire to secure by Letters Patent is:

1. A doll having in combination a readily collapsible elastic torso cover, a separately formed resilient torso supporting and substantially filling said cover, limbs separately formed and independently attached to said cover, a neck member within and supporting a part of said cover and a separately formed head seated upon said cover above and attached to said neck member, said attachment of head and limbs being adapted to permit the same to be rotated and retained in a variety of postures.

2. A doll having in combination a readily collapsible elastic torso cover having reinforcing means in the region of the shoulders and hips, a separately formed resilient torso supporting and substantially filling said cover, limbs separately formed and independently attached to said cover, a neck member within and supporting a part of said cover and a separately formed head seated upon said cover above and attached to said neck member, said attachment of head and limbs being adapted to permit the same to be rotated and retained in a variety of postures, the means for said attachment of each limb to cover including

a member piercing said reinforcing means and anchored within the same.

3. A new article of manufacture, a pre-formed readily collapsible elastic rubber cover for a doll's 5 torso, having an expansible opening in said cover, and having its surface substantially closing each of the shoulder and hip regions.

4. A doll having in combination an elastic readily collapsible torso cover and a pre-formed

10 resilient torso and a neck member associated therewith substantially filling and serving as the sole support for said torso cover and separable therefrom, said torso having recesses formed in its hip and shoulder regions.

15 5. The method of making a doll which includes the steps of making separately a resilient torso, a readily collapsible elastic torso cover having an expansible opening therein, limbs and a head, attaching said limbs separately to said torso cover

20 by means adapted to permit relative rotative movement of said parts, inserting said torso within said cover by expanding said opening, and attaching a head to said torso by means permitting movement of said head.

25 6. The method of making a doll which includes the steps of making separately a resilient torso, a readily collapsible elastic torso cover having an opening therein, limbs, a head and a neck member, attaching said limbs separately to said

30 torso cover by means adapted to permit relative rotative movement of said parts, inserting said torso and neck member within said cover by expanding said opening and attaching a head to said neck member by means permitting movement of said head.

35 7. The method of making a doll which includes

the steps of making separately a readily collapsible elastic torso cover having an expansible neck opening, a resilient torso of predetermined shape, and limbs, attaching said limbs to said torso cover by means which include members passing through said torso cover and anchored within said cover, and inserting said torso within said cover by expanding the opening of said torso cover.

8. The method of making a doll which includes 10 the steps of making separately a readily collapsible elastic torso cover having an expansible neck opening, a resilient torso of predetermined shape, and limbs, attaching said limbs to said torso cover by means which include members 15 passing through said torso cover and anchored within said cover, and inserting said torso within said cover by expanding the opening of said torso cover, and attaching a head to said doll by means which include a relatively rigid neck member inserted within said cover through said opening.

9. A doll having in combination a pre-formed readily collapsible elastic rubber torso cover, independent and separately movable limbs carried solely by said cover and a pre-formed torso element contained within said cover and serving as substantially the sole supporting and filling means therefor.

10. A new article of manufacture, a pre-formed readily collapsible rubber cover for a doll's torso 30 having an expansible opening in said cover, and substantially closed portions thereof at the shoulder and hip regions, said portions having incorporated therein reinforcing means adapted to resist tear.

35 ANDREW HAJDU.
